CLAIM

The ornamental design for a palm-held liquid and lotion applicator, as shown and described.

DESCRIPTION

FIG. 1 illustrates a top perspective view of a palm-held liquid and lotion applicator showing my new design;

FIG. 2 illustrates a side view, the opposite side is a mirror image thereto except for the continuous screw threading on the neck;

FIG. 3 illustrates a bottom perspective view thereof;

FIG. 4 illustrates a bottom plan view thereof;

FIG. 5 illustrates a top perspective view of a second embodiment of the palm-held liquid and lotion applicator;

FIG. 6 illustrates a side view of the second embodiment, the opposite side view is a mirror image thereto except for the continuous screw threading on the neck; and,

FIG. 7 illustrates a top plan view of the second embodiment, the bottom plan view is a mirror image thereto except for the continuous screw threading on the neck.
